UNITED STATES PATENT OFFICE.

HENRY CHANNON, OF CHICAGO, ILLINOIS.

EXCAVATING-BUCKET.

No. 868,595.

Specification of Letters Patent.

Patented Oct. 15, 1907.

Application filed May 4, 1907. Serial No. 371,887.

To all whom it may concern:

Be it known that I, HENRY CHANNON, a citizen of the United States, residing at Chicago, county of Cook, State of Illinois, have invented a certain new and useful Improvement in Excavating-Buckets, and declare the following to be a full, clear, and exact description of the same, such as will enable others skilled in the art to which it pertains to make and use the same, reference being had to the accompanying drawings, which

10 form a part of this specification.

My invention relates to excavating apparatus and more particularly to a bucket for use in power-operated excavating apparatus.

In my prior patent, No. 832,894, granted October 8, 15 1906, there is disclosed a novel form of bucket adapted to be used in excavating by power, the bucket being so arranged that it may be drawn into the material to be excavated, lifted, carried to the spoil pile, and there dumped, by simply controlling the cables which 20 are employed to support it and to draw it into the material to be excavated. Experience has demonstrated that an apparatus of this kind which is properly designed to excavate material of one character may not work at all satisfactorily when it is attempted to excavate material of a different character. Thus, an 25 apparatus for use in excavating sand must be arranged differently from one which is intended to operate upon clay. Furthermore, the compactness or hardness of the material in the mass from which it 30 is to be excavated also affects the operation of the apparatus.

The object of my invention is to provide a bucket of the character described which may be quickly and conveniently adjusted so as to enable it to operate 35 efficiently for excavating materials differing widely in character, and from masses which vary in hardness and compactness.

The various features of novelty which characterize my invention will be hereinafter pointed out with 40 particularity in the claims; but for a full understanding of my invention in its various aspects reference is to be had to the following detailed description taken in connection with the accompanying drawing, wherein:

45 Figure 1 shows in side elevation a bucket arranged in accordance with the preferred form of my invention; and Fig. 2 is a plan view of the bucket shown in Fig. 1.

Referring to the drawing; A represents a bucket 50 having any desired shape and size, and being made of any suitable material. The bucket illustrated is indicated as being of sheet metal, and comprises side walls A' and A², a rear wall A³, and a bottom wall A⁴ having a cutting edge a at the front end. The bucket 55 is therefore open at one end and at the top.

In order to stiffen the bucket, a U-shaped metal

plate A⁵ is arranged across the top of the open end and secured to the side walls thereof.

B indicates a supporting bail between the lower ends of which the bucket is pivotally mounted. The 60 point at which the bucket is supported on the bail is in the rear of the center of gravity of the bucket so that, when free to do so, the front end of the bucket drops downward and causes the contents to be discharged.

65

C is a bail pivotally connected to the front end of the bucket and the bucket is forced into the material to be excavated so as to take up its load, by drawing upon this bail.

D, D are rods connecting the bails B and C together; 70 there being one of these rods on each side of the bucket and each of the rods being preferably provided with a turn-buckle D'. The points of connection between the bail C and the bucket are beneath the rods D so that, in order for the front end of the bucket to drop 75 while the supporting bail remains vertical, the bail C must be swung upwardly. Therefore, after the bucket has taken up its load, it may be moved to the spoil pile by drawing upon the bail at the front end so as to maintain the bail horizontal. When the spoil pile is 80 reached, the pulling rope is slackened and the bail is free to swing upwardly and permit the bucket to discharge its load. In order to prevent the material in the bucket from falling out of the front end during the 85 passage of the bucket to the spoil pile, the bottom of the bucket is preferably held tilted backward; the extent of tilting depending upon the character of the material being operated upon; and the tilting being produced by adjusting the turn-buckles in the side rods.

90

It has been found that when the bucket is drawn upon so as to cause it to enter the material to be excavated, it is liable to tilt upwardly to such an extent that little or no material is taken up thereby during the entire travel of the bucket unless the nicest adjustments between 95 the various parts are made. I have found that this difficulty may be overcome by providing means for shifting the points of connection between the bails and the bucket so as to vary the line of pull upon the bucket to suit the conditions under which the bucket is being 100 operated. The position of the pivots of the pulling bail is of particular importance. These adjustments may be made in various ways. A convenient arrangement for this purpose consists in pivoting the bails, not directly to the bucket, but to an independent support 105 which may be adjusted upon the bucket into various positions so as to raise or lower either of the pivotal axes or carry these axes toward the front or toward the rear of the bucket within such limits as the range of materials which it may be desired to operate upon may require.

In the drawing E, E represent two flat plates or bars

one of which is arranged on each side of the bucket. Each of the members E is provided with a series of distributed holes e at one end and a second series of distributed holes e' at the other end. These members are 5 secured to the sides of the bucket by means of bolts e² and e³ which pass through the walls of the bucket and through any pair of openings in the ends of the members. The bail B is pivoted to these members at b and the bail C is pivoted to the front ends of the members as 10 at c. To provide for further adjustment, the pivotal points of the supporting bail upon the members may be shifted by placing the pivots in any pair of a series of openings e⁵ in the members E. It will be seen that the supporting members for the bail may be raised and 15 lowered, or they may be moved backward or forward, so that the pull upon the bail at the front end of the bucket may be directed along any desired line. Furthermore, the pivotal axis of the bucket upon the supporting bail may be conveniently shifted so as to bring 20 it in any desired relation to the center of gravity of the loaded bucket and thereby facilitate the conveying and dumping of the load. The side members are preferably so located that the points of connection between the pulling bail and the bucket may be shifted within limited 25 distances above and below the center of gravity, thereby making it possible to greatly vary the effect of the pull upon the bucket.

It is desirable to use a bucket having its bottom wall connected to the rear wall by a rounded portion, as this 30 construction prevents the material from becoming lodged in the bucket. However, such a bucket is apt to rock backwardly and discharge part of the load before the bucket is lifted. To overcome this objection I place one or more runners, such as F beneath the bucket, 35 the runners being so arranged that the effect of a flat bottom bucket is produced. It will be seen that the runners also protect the bottom of the bucket against the wear due to dragging the bucket across the surface of the material which is being excavated.

40 While I have described in detail a preferred form of my invention, I do not desire to be limited to the particular details of construction shown, since in its broader aspect my invention contemplates various other forms which operate to bring about the beneficial result obtained by the mechanism illustrated.

Having now fully described my invention, what I claim as new and desire to secure by Letters Patent is:

50 1. In a device of the character described, the combination with an excavating bucket, of a supporting member pivoted to said bucket at the rear of its center of gravity, means for varying the point of connection between the bucket and the supporting member, and holding mechanism secured to said supporting member and connected to the bucket in front of its center of gravity.

2. In a device of the character described, the combination with an excavating bucket, of a supporting member pivoted to said bucket at the rear of its center of gravity, holding mechanism secured to said supporting member and connected to the bucket in front of the center of gravity, and means for varying the point of connection between 60 said holding mechanism and the bucket.

3. In a device of the character described, the combination with a bucket, of a supporting bail between the arms of which the bucket is situated, means for pivotally supporting the bucket from said bail at any one of a series of 65 points in the rear of the center of gravity of the bucket, and pulling mechanism secured to the portions of said bail on opposite sides of the bucket, said mechanism being connected to each side of the bucket in front of its center of gravity.

4. In a device of the character described, the combination with a bucket, of a supporting bail, means for pivotally supporting the bucket upon the supporting bail at any one of a number of points at the rear of the center of gravity of the bucket, a second bail, and means for pivotally connecting said bails together.

5. In a device of the character described, the combination with an excavating bucket, a pair of side members adjustably secured to the side walls of the bucket, a supporting bail for said bucket pivotally connected at its 80 ends to said side members, and pulling mechanism secured to the front ends of said side members and connected to said bail.

6. In a device of the character described, the combination with a bucket, a pair of side members secured to the 85 side walls of the bucket, means for adjusting the position of said members in two directions at right angles to each other, a supporting member for the bucket pivoted to said side members in the rear of the center of gravity of the bucket, a pulling member secured to the front ends of said 90 side members, and a connection between the supporting member and the pulling member.

7. In a device of the character described, the combination with a bucket, a pair of side members adjustably mounted on the side of the bucket, a supporting bail for 95 said bucket, means for pivotally connecting said supporting bail to said side members at any one of a plurality of points, a pulling member secured to the front ends of said side members, and a connection between the supporting bail and the pulling member.

8. In a device of the character described, the combination with a bucket, of a supporting member pivoted to said bucket, means for varying the point of connection between said member and the bucket, pulling mechanism engaging said supporting member and connected to the bucket, and means for adjusting the pulling mechanism to vary the inclination of the bucket.

9. In a device of the character described, the combination with an excavating bucket, of a supporting member connected to said bucket at the rear of the center of gravity, a pulling member connected to said bucket in front of the center of gravity, means for adjusting the point of the pulling member above or below the center of gravity of the bucket.

In testimony whereof, I sign this specification in the 115 presence of two witnesses.

HENRY CHANNON.
